(57) **CLAIM**

The ornamental design for a table, as shown and described.

DESCRIPTION

FIG. 1 is a front perspective view of a table showing my new design;

FIG. 2 is a front elevational view thereof;

FIG. 3 is a side elevational view, the opposite side being a mirror image thereof;

FIG. 4 is a rear elevational view thereof;

FIG. 5 is a top view thereof; and,

FIG. 6 is a perspective view of a table showing my new design in a nested arrangement.

The views of the table not shown form no part of the claimed design. The broken lines depicting rails and nested arrangement of tables represent environmental elements only and form no part of the claimed design.

1 Claim, 6 Drawing Sheets
